(57) CLAIM

The ornamental design for a light fixture, as shown and described.

DESCRIPTION

FIG. 1 is a perspective view of an embodiment of the claimed design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The ornamental design that is claimed is shown in the drawings as solid lines and surfaces having surface shading. The broken lines illustrating portions of the light fixture form no part of the claimed design. Break lines having a jagged element are not part of the claimed design. The appearance of any portion of the article between and beyond the break lines forms no part of the claimed design.
